HIGH POWER PROJECTION OSCILLOGRAPH

Philo T. Farnsworth, San Francisco, and Frank J. Somers, San Jose, Calif., assignors to Farnsworth Television Incorporated, San Francisco, Calif., a corporation of California

Application November 2, 1936, Serial No. 108,723

3 Claims. (Cl. 178—7.7)

Our invention relates to projection oscilloscopes, and more particularly to such oscilloscopes utilizing a luminous screen wherein light is produced by incandescence rather than by 5 fluorescence.

In cathode ray tubes where the image is produced on a screen by raising elementary areas thereof to incandescence by the impact of a cathode ray beam, the principal difficulties have 10 been first, to obtain sufficient power to excite the heat screen at low cathode ray gun voltages, and second, to provide a screen having a sufficiently low mass so that heat losses may be confined almost wholly to radiation.

15 Another difficulty, an outgrowth of the first two above-mentioned, is that it is desirable to make the picture area of the heat screen relatively small, preferably of standard motion picture frame size, so that economical lenses may be used 20 for projection of the image. When such a relatively small screen is used, it is obvious that a very fine scanning spot is necessary to obtain high fidelity images, and a fine spot is inconsistent with high gun currents.

25 It is therefore the main object of our present invention to provide a cathode ray tube of the heat screen type, wherein the gun current can be kept low in order to obtain a fine scanning spot.

30 Another object of our invention is to provide a high illumination screen, even though a small scanning spot is used, and to be able to use a relatively low gun anode voltage.

35 A further object of our invention is to provide an exceedingly high voltage on the screen itself, and to generate this voltage close to the screen and by the use of high frequency oscillators, in order to minimize distortion due to electrostatic stresses.

40 A still further object of our invention is to utilize secondary emission to increase the number of electrons reaching the heat screen; and again, it is also an object of our invention to feed power to the electrons bombarding the heat 45 screen after deflection.

Our invention possesses numerous other objects and features of advantage, some of which, together with the foregoing, will be set forth in the following description of specific apparatus 50 embodying and utilizing our novel method. It is therefore to be understood that our method is applicable to other apparatus, and that we do not limit ourselves, in any way, to the apparatus of the present application, as we may adopt various 55 other apparatus embodiments, utilizing the

method, within the scope of the appended claims.

Referring to the drawing:

The figure is diagrammatic and reduced to lowest terms, and comprises a sectional view of a preferred tube embodying our invention, together with a sectional view of a preferred oscillator and circuits connecting the two for operation. 5

Our novel method of operating a cathode ray tube, together with one preferred means for 10 practicing the method, may be more fully understood by direct reference to the figure.

The cathode ray tube comprises an envelope 1 provided at one end with a window 2 and at the other end with a reentrant stem 4. On this 15 reentrant stem we mount a gun heater 5, a gun cathode 6 and a thimble grid 7 having a central aperture 8 through which electrons pass to enter the beam canal 9 of a gun anode 10.

The cathode, grid and anode of the gun are 20 alined to project a beam of electrons of low power into the envelope space 11 and toward a luminescent screen 12 which is preferably formed of refractory material of low mass, such as, for example, an extremely thin sheet of tantalum or 25 tungsten, or the screen may be knitted from fine refractory wires to have a mesh smaller than the elementary area it is desired to reproduce, or again, it may comprise parallel rows of refractory wire spirals; in fact, there are many forms in 30 which this screen may be made, the main factor being that it shall have low mass so that heat losses may be confined almost wholly to radiation, and that it shall have an elementary structure such that all desired detail may be reproduced 35 thereon.

A secondary emission screen 14 is provided between anode 9 and heat screen 12, preferably closer to the heat screen than to the anode. The envelope chamber 11 between anode 9 and 40 secondary emission screen 14 is preferably wall-coated with a silver or nickel film 15, and this wall film is connected directly to secondary emission screen 14 at one end and provided with an external lead 16 at any convenient point. Heat 45 screen 12 is provided with an external lead 17, anode 9 with its lead 19, and the various gun elements are provided also with their respective leads, as is customary in the art.

For operation, gun heater 5 may be energized 50 from alternating current mains through transformer 20; gun cathode 6 is connected to ground; gun anode 9 and film 15 are connected together in a combined supply lead 21; and thimble grid 7 is provided with the usual bias through biasing 55

resistor and battery 22 so that the gun current may be accurately regulated.

Scanning oscillators 24 and 25 energize scanning coils 26 and 27 in order that their fields may move the beam issuing from beam canal 9 in two directions over secondary emission electrode 14, and a projection lens 29 is provided so that the image formed on heat screen 12 may be projected on any convenient viewing surface. In order that the scanning spot or cross section of the scanning beam may be kept as small as possible, we prefer to surround the beam path with a focusing coil 30, energized by focusing battery 31 under the control of resistor 32.

So far we have described all connections to the tube except the voltage supply to anode 10 and secondary emitter 14, and to the heat screen 12. We prefer to supply voltage to the heat screen from a high frequency oscillator 35. This oscillator may be any oscillator capable of a high frequency output, such as three megacycles, for example, although we prefer to utilize a multipactor oscillator for this purpose. Such an oscillator has been described by Philo T. Farnsworth in his application for United States Letters Patent, Serial No. 61,042, filed Jan. 27, 1936, and comprises an envelope containing a secondary emissive cathode 36, a perforated anode 37 and a central ion collector 38.

The multipactor cathode and anode are connected together through a tuned circuit 39 which forms the primary of a direct-coupled transformer, the secondary 40 of which is connected to lead 17 and thence to heat screen 12. Multipactor anode voltage is supplied by anode battery 41, and lead 21 is connected to this battery through radio frequency choke 42, thus providing steady voltage for gun anode 10. The cathode-anode circuit of the multipactor contains a blocking condenser 43 to prevent anode voltage reaching the cathode. Ion collector 38 is connected to ground through an ion control source 44 so that ion control electrode 38 is slightly negative to pick up any free ions in the multiplier space.

Such a tube is a self-oscillator at high frequencies, oscillating power being developed by repeated impacts of primary electrons against cathode 36, which is preferably treated or otherwise formed in such a manner that for each primary impacting it, two to ten secondaries will be emitted. The action of this type of oscillator is well known in the art, due to Farnsworth's publications, and no further explanation is deemed necessary.

In operation, we shall describe a particular tube and give the voltages which have been found, by experimentation, to be satisfactory in the operation of that particular tube, and it will be well within the knowledge of those skilled in the art to understand the energization and operation of other examples.

We prefer to utilize the gun to produce a gun current of about one milliamper, with the relatively low gun anode voltage of fifteen hundred volts. This means that the beam issuing from beam canal 9 may be of very small diameter and may be kept at a small diameter until it reaches secondary emission electrode 14 to form an exceedingly fine spot thereon. In addition, due to the fact that the gun anode has such a low voltage, and because there is a small diameter beam, the scanning sensitivity of the cathode ray beam to deflection is maintained high.

We then prefer to form the secondary emission

screen 14 in such a manner that it will generate copious secondary emission when the electrons in the beam bombard it, and we have found that we can so treat this screen that secondaries in the ratio of one to one may be obtained with impact voltages as low as twenty volts, with a total secondary production for each primary of as high as ten to one. We form the screen 14 of relatively fine wire so that even though the mesh count of the screen 14 is greater than the number of elements desired in the image, there is still plenty of aperture area.

When oscillators 24 and 25 are set in operation, the beam is moved to produce a picture area on the screen 14. Obviously, some of the primaries in the beam will pass through the apertures in screen 14 without creating secondaries. Other primaries in the beam will, however, impact the wires of screen 14 and generate secondaries. Consequently, there may be available, in the plane of the screen 14, both primaries and secondaries. If, then, oscillator 35 is set into operation so that the transformer 39-40 will supply the heat screen 12 with approximately fifty to seventy five kilovolts R. M. S. at a frequency of about three megacycles, both primaries and secondaries will be pulled through screen 14 and tremendously accelerated before they impact heat screen 12. The radio frequency current applied to the heat screen is, of course, self-rectified within the tube. The frequency of the multiplier oscillator is chosen high enough so that there will be several cycles at least of the radio frequency per picture element, and there will, therefore, be no matte effect produced in the picture from this source. At the same time, frequencies in the neighborhood of three megacycles are low enough to allow the use of high Q coils, efficient oscillator operation and efficient voltage step-up in the transformer 39-40.

Inasmuch as primaries and secondaries are only emitted from screen 14 at the point of scansion, it is obvious that only corresponding points on heat screen 12 will be bombarded, and due to the acceleration between screens 14 and 12, as a consequence of the extreme high voltage on screen 12, the wires of screen 12 at the point of electron impact will become incandescent and illuminated in accordance with the modulation of the original scanning beam. It is therefore obvious that by supplying the majority of power in the tube as an accelerating potential on the final screen, the beam itself may be made of sufficiently low power so that it may be sensitive to deflection and have an extremely small cross section, thus eliminating the objections to primary guns of high power.

There is, however, another very important feature in the use of a high frequency alternating potential on screen 12. Screen 12 is adapted to be raised to incandescence by electron impact. It is obvious, therefore, that the mass of the wire from which screen 12 is woven must be small in order to reduce heat conduction along the wires, and in order that the mass may be raised to incandescence without substantial lag. The material of the screen may be tungsten or tantalum wire, for example, between .005" and .0005". The type of mesh of the screen may be, and preferably is, that of a knitted fabric, in order that the individual wires thereof may be longer than the distance between their points of attachment to the support frame. By utilizing such a knitted screen or a similar inherently elastic

mesh, it is possible, as far as the differential heating of the screen is concerned, to maintain the screen in its normal plane. There are, however, other and much greater forces acting on the screen, particularly if a high steady voltage were to be employed upon screen 12 for acceleration purposes.

Following the examples herein given, it will be noted that screen 14 has upon it a steady potential of fifteen hundred volts, and it is desired, in order to obtain high electron velocities, to place fifty to seventy-five thousand volts or more upon screen 12. It is obvious that if this high voltage were steady, that there would be large electrostatic stresses set up between screen 12 and screen 14, or between screen 12 and charges on the adjacent tube walls. Such stresses could only be eliminated by wide spacing between adjacent screens, and by the enlargement of the envelope 20 to a point where electrostatic charges on the walls thereof would not be sufficient to place a stress upon screen 12. Such spacings, however, are highly impractical, and with spacings demanded by modern design, the electrostatic stresses set up by a steady potential on screen 12, under the voltages mentioned, are sufficient to completely destroy the utility of screen 12, inasmuch as it is inherently elastic and will distort freely under stresses much less than those encountered in the example given.

If, however, the screen 12 is energized by an alternating potential, particularly an alternating potential which is of sufficiently high frequency so that the screen 12 cannot move under the influence of the rapidly changing and reversing electrostatic stresses, it is obvious that the screen 12 will stay in its predetermined plane. It is only necessary, therefore, to apply an alternating potential having a frequency that is substantially higher than the natural period of vibration of screen 12, and having, in case that the screen 12 is to be used as an image producer where elemental areas are to be formed thereon, the frequency sufficiently high so that there will be sev-

eral cycles of the high frequency per picture element.

It is, however, to be distinctly understood that we also wish to use the method of energizing inherently elastic screens with high frequency potentials in all cases where such screens would normally, under the influence of a steady potential, be subject to electrostatic stresses causing distortion of the screen, irrespective of whether or not the screen is to be used as a light source, 10 an accelerating electrode, or in any other fashion within a thermionic tube.

We claim:

1. A cathode ray tube comprising an envelope containing a source of electrons, a collecting electrode normally distortable by the electrostatic stresses set up when energized to a predetermined steady collection potential, an oscillator connected to said electrode, and circuits maintaining the frequency of said oscillator substantially higher than the natural period of said collecting electrode. 15

2. A cathode ray tube comprising an envelope containing a source of electrons, a collecting electrode comprising a fine wire screen normally distortable by the electrostatic stresses set up when energized to a predetermined steady collection potential, an oscillator connected to said electrode, and circuits maintaining the frequency of said oscillator substantially higher than the natural period of said collecting electrode. 25

3. The method of developing an incandescent image on a heat screen in a cathode ray tube which comprises generating a stream of electrons having an elemental cross section, scanning a picture area with said beam, generating secondary electrons with part of said beam at each elemental area scanned, combining said secondary electrons with the remainder of said beam, and energizing said screen with an alternating potential at a frequency substantially higher than the number of elements involved. 35 40
